HOMOGENIZING MECHANISM

William Spencer Bowen and Julius Freeman,
Westfield, N. J.

Application February 16, 1934, Serial No. 711,614

9 Claims. (Cl. 99—266)

The present invention relates to homogenizing mechanisms and embodies, more specifically, an improved homogenizing device wherein means is provided to regulate, properly, the rate of feed of substance to the mechanism, as well as discharge controlling means whereby the homogenized substance may be discharged from the homogenizing chamber in a desired fashion. The invention further includes a homogenizing mechanism having an improved feeding device by means of which the homogenization of substance may be accomplished more effectively.

More particularly, the invention embodies certain features which have been designed for use in connection with the copending application of William Spencer Bowen, Ser. No. 712,132, filed February 20, 1934, and although shown as embodied in a structure following that described and shown in the above identified pending application, it is obvious that the features may be applied to many forms of mechanisms designed for performing operations similar to those performed by the mechanism described herein. The particular features above referred to include an improved spray head construction by means of which substance may be fed uniformly and effectively to the homogenizing head whereby a more uniform homogenization is accomplished, as well as an improved suction control for the feeding of substance to the homogenizer. This control is designed to be responsive to the suction created by the homogenizer head and varies the supply of substance to the head in accordance with the capacity of the head to homogenize the same. The invention further contemplates the provision of a discharge mechanism controlled by the pressure produced by the homogenizing head in operation, the building up of sufficient pressure thereby serving to actuate the discharge mechanism in a suitable fashion.

Other objects and advantages of the invention will appear as it is described in further detail in connection with the accompanying drawings, wherein:

Figure 1 is a view in section, taken through the axis of a homogenizing mechanism constructed in accordance with the present invention, and showing the various features of the invention.

Figure 2 is a view in end elevation partly broken away and in section showing the driving mechanism for the homogenizing head.

Figure 3 is a plan view, partly broken away and in section, showing the construction of the homogenizing head.

Figure 4 is an enlarged view in section, simi-

lar to Figure 1, and showing the details of an element of the supply mechanism for the homogenizing head.

Figure 5 is a view in section, taken on line 5—5 of Figure 4, and looking in the direction of the 5 arrows.

Figure 6 is a segmental view in section, showing an improved form of discharge mechanism constructed in accordance with the present invention.

Figure 7 is a view in end elevation of the mechanism of Figure 6.

Referring to the above drawings, the homogenizer is shown in Figure 1 as being formed with a bell-shaped housing 10 which forms a homogenizing chamber 11, the housing having an inwardly and upwardly sloping top wall 12 and a downwardly and inwardly sloping bottom wall 13. The formation of the top wall 12 causes the device to be self-scavenging and the housing is adapted to receive a cover plate 14 within which a hollow shaft 15 is journaled by means of a bearing 16. A sealing member 17 is provided to form a seal between the cover plate 14 and the rotatable hollow shaft 15 and the assembly may be secured to the housing 10 by means of bolts 18.

Mounted upon the cover plate 14 is a housing 19 which may be secured to the plate by means of bolts 20 and which is provided with a bearing 21 in which the hollow shaft 15 is journaled. The 30 housing 19 is formed with a turbine chamber 22 within which a turbine wheel or rotor 23 is received. This rotor is secured to the hollow shaft 15 and is formed of a plurality of vanes, as shown in Figure 2. Fluid under pressure is directed 35 against the vanes 23 by means of a nozzle 24 (Figure 2) which receives fluid from a supply pipe 25 through a balanced valve mechanism 26. The balanced valve is actuated by a spindle 27 which is controlled in a manner to be described 40 hereinafter and the fluid is discharged from the chamber 22 through an outlet 28.

Adjacent the bottom of the hollow shaft 15 a plurality of axially extending slots 29 are formed, these slots opening into a homogenizing head 30 (Figure 3). The homogenizing head is provided with a plurality of substantially radially extending blades 31 having forwardly extending fins 32 and inwardly extending fins 33 formed thereon. 45 The substance is directed outwardly under great centrifugal force and strikes against the surfaces of the fins 32 and is subjected to shearing stresses in passing over the edges thereof. Effective homogenization is thereby produced. The lower 50

55

end of the hollow shaft 15 is closed by means of a cap 34 or other device.

As described in the copending application, above referred to, the supply of driving fluid from the pipe 25 to the turbine wheel is controlled by a floating plate 35 which is journaled at 36 upon the housing 19. This plate is provided with a plurality of U-shaped permanent magnets 37 the poles of which lie directly under and in close proximity to a disc 38 which is secured to the upper end of the hollow shaft 15. Upon the lower face of the plate 35 a cam 39 is formed, this cam being adapted to engage a roller 40 which is mounted upon the spindle 27. A spring 41 normally urges the roller against the under side of the plate 35 when the cam 39 engages the roller inasmuch as rotation of the disc 38 over the poles of the magnets 37 subjects the plate 35 to a driving torque which causes it to tend to follow rotation of the disc 38. The cam 39 is moved against and over the roller 40. If the speed of the micronizer head should increase momentarily, the cam 39 depresses the spindle 27 and partially closes the valve 26, thus cutting down the supply of fluid to the driving mechanism. As a result the speed will be decreased and a nice and effective control of the speed of the head will thus be obtained.

Within the rotatable hollow shaft 15 is mounted a stationary feed shaft 42, labyrinth packing glands 43 being provided therebetween to produce an effective seal between the relatively rotatable members. The lower end of the stationary shaft 42 is provided with a plurality of vanes 44 which are preferably curved in the direction of rotation of the micronizer head to impart an initial whirl to the particles supplied through the feed pipe 42. The bottom of the pipe is formed as a conical seat 45 against which a conical valve 46 is adapted to engage, the valve being mounted upon a central spindle 47 which is slidably mounted at the axis of the vanes 44 and may be manually adjusted by means of a knurled knob 48 at the outer extremity thereof.

45 The shaft 47 is threaded in a cap 49 which is secured to an extension 50 of a fitting 51. The fitting 51 is secured to the top of the feed pipe 42 and has an L connection 52 which is connected to a supply pipe 53. A valve 54 is connected 50 in the supply pipe and thus serves as a means for controlling the supply of substance to the homogenizing mechanism. The movable element of the valve 54 is connected to a spindle 55 which is actuated by a pressure responsive device 56 through a suitable connection 57. The pressure responsive device 56 communicates with the extension 50 of the fitting 51 through a suction pipe 58. In this fashion, when the suction within the feed pipe 42 increases, due to increased speed of the micronizer head, the valve 54 is opened wider to permit a greater amount of substance to be fed to the micronizer head. Inasmuch as the extension 50 of the fitting 51 is not directly in the feed line, the suction pipe 58 will 60 not receive any of the substance which is supplied to the micronizing mechanism and is only responsive to the suction within the feed pipe and head.

As the substance is homogenized, it is directed 70 outwardly into the chamber 11 and moves into the mouth 59 thereof. This mouth may be closed by means of a gate or other valve 60 which is actuated by a stem 61 and a pressure responsive device 62 through a link or other connection 63. The pressure responsive device 62 communicates

with the interior of the housing 10 through a pressure pipe 64 and, as the pressure within the chamber builds up due to an accumulation of homogenized substance therein, the device 62 is actuated to open the valve 60 and permit the 5 contents of the chamber to be discharged.

A modified form of discharge mechanism is shown in Figures 6 and 7 and includes a device whereby measured quantities of the homogenized substance may be discharged from the device 10 as it accumulates within the homogenizing chamber. The outlet of the housing 10, in this form of the invention, is provided with a lug 65 within which a measuring wheel 66 is journaled as at 67. This wheel is formed with a plurality 15 of wells 68 of predetermined size, the wells being closed by flaps 69 which are hinged at 70 to the bottom of the respective wells. As the wells are moved in position beneath the outlet 59 the gates are closed by means of rollers 71 and thus permit 20 the respective wells to be filled with substance which is discharged from the outlet 59 under pressure.

The measuring wheel 66 may be driven by a ratchet and pawl or rack and pinion mechanism 25 indicated at 72, this driving mechanism being actuated by the pressure responsive device 62 which communicates with the interior of the homogenizing chamber. In this fashion measured quantities of the homogenizing substance 30 may be discharged under pressure as it accumulates within the homogenizing chamber.

While the invention has been described with specific reference to the accompanying drawings, it is not to be limited, save as defined in the appended claims.

We claim as our invention:

1. A homogenizing apparatus comprising a chamber forming housing, a homogenizing head therein, a feed pipe to direct a substance to the head, means to control the flow of substance through the feed pipe, and means responsive to pressure within the pipe to actuate the control means.

2. A homogenizing apparatus comprising a 45 chamber forming housing, a homogenizing head therein, a feed pipe to direct a substance to the head, means to control the flow of substance through the feed pipe, said pipe being formed with a space out of the direct path of the pipe 50 and subject to the pressure within the pipe, and pressure responsive means communicating with said space to actuate the control means.

3. A homogenizing apparatus comprising a chamber forming housing, a hollow feed pipe 55 journaled on the housing and having a homogenizing head thereon within the housing, means to control the flow of a substance through the feed pipe, and means responsive to the pressure within the feed pipe to actuate the control means. 60

4. A homogenizing apparatus comprising a chamber forming housing, a hollow feed pipe journaled on the housing and having a homogenizing head thereon within the housing, a stationary pipe communicating with the first pipe, 65 means to control the flow of a substance through the stationary pipe, and means responsive to the pressure within the stationary pipe to actuate the control means.

5. A homogenizing apparatus comprising a 70 chamber forming housing, a hollow feed pipe journaled on the housing and having a homogenizing head thereon within the housing, a stationary pipe communicating with the first 75

pipe, a seal between the stationary pipe and the first pipe, means to control the flow of a substance through the stationary pipe, and means responsive to the pressure within the stationary pipe to actuate the control means.

5. 6. A homogenizing apparatus comprising a housing, a rotatable head in the housing, a feed pipe associated with the head and communicating with the central interior thereof, a nozzle on the 10 feed pipe to direct a substance into the head, means to impart a whirl to the substance before it reaches the head, and means to vary the opening of the nozzle.

7. Apparatus for controlling a homogenizer 15 having a chamber forming housing, a homogenizing head in the housing to introduce a medium thereinto and create a pressure therein, and an outlet for the housing, said apparatus comprising a closure for the housing, and means actuated by pressure within the housing to operate

the closure whereby a pressure will be maintained within the housing.

8. Apparatus for controlling a homogenizer having a chamber forming housing, a homogenizing head in the housing to introduce a medium 5 thereinto and create a pressure therein, and an outlet for the housing, said apparatus comprising a closure for the housing formed with means to discharge predetermined amounts therefrom, and means to actuate the closure by pressure 10 within the housing whereby a pressure will be maintained within the housing.

9. A homogenizing apparatus comprising a housing, a rotatable head in the housing having a closed end and an axial recess, stationary means 15 in the recess to direct a substance radially into the head, and means to impart a whirl to the substance before it reaches the head.

WILLIAM SPENCER BOWEN.
